(57) **CLAIM**

The ornamental design for a fluid dispensing tap, as shown and described.

DESCRIPTION

FIG. 1 is a top view of a fluid dispensing tap, showing our new design;

FIG. 2 is a left side view thereof;

FIG. 3 is a front view thereof;

FIG. 4 is a right side view thereof;

FIG. 5 is a back view thereof;

FIG. 6 is a bottom view thereof;

FIG. 7 is a perspective view showing the top and back views thereof;

FIG. 8 is a perspective view showing the left and top views thereof;

FIG. 9 is a perspective view showing the top, front and right views thereof;

FIG. 10 is a perspective view showing the bottom, right and back views thereof;

FIG. 11 is a perspective view showing the bottom and back views thereof; and,

FIG. 12 is a perspective view showing the bottom, and front views thereof.

The broken lines in the drawings illustrate portions of the fluid dispensing tap that form no part of the claimed design.

1 Claim, 12 Drawing Sheets
